Primary Examiner — Thomas Johannes*Assistant Examiner* — Shawn T Gingrich(74) *Attorney, Agent, or Firm* — Wei Te Chung; Ming Chieh Chang(57) **CLAIM**

The ornamental design for an electrical connector, as shown and described.

DESCRIPTION

FIG. 1 is a perspective view of an electrical connector showing our new design;

FIG. 2 is a top plan view thereof;

FIG. 3 is a bottom plan view thereof; and,

FIG. 4 is a cross-sectional view of the electrical connector taken along line 4-4 of FIG. 1.

The broken line portion of the figure drawing is included to show portions of the article that forms no part of the claimed design, and the dash-dot line portion of the figure drawing represents the boundary that forms no part of the claims design.

1 Claim, 4 Drawing Sheets(56)
